178,975

GOLF CLUB CART

George J. Traut, Englewood, Colo.

Application January 17, 1955, Serial No. 34,004

Term of patent 7 years

(Cl. D14—3)

Fig. 1 is a plan view of a golf club cart showing my new design;

Fig. 2 is a right side view thereof; and

Fig. 3 is a rear view thereof.

I claim:

The ornamental design for a golf club cart, as shown.

References Cited in the file of this patent

UNITED STATES PATENTS

2,411,965	Hartung	Dec. 3, 1946
2,681,232	Womack	June 15, 1954
2,681,810	Lowinski	June 22, 1954